(57) CLAIM

The ornamental design for a lounge chair, as shown and described.

DESCRIPTION

FIG. 1 is a front and right side perspective view of an exemplary lounge chair showing my new design;

FIG. 2 is a front elevation view thereof;

FIG. 3 is a right side elevation view thereof, the left side being a mirror image;

FIG. 4 is a top plan view thereof;

FIG. 5 is a rear elevation view thereof; and,

FIG. 6 is a close-up view of a weave pattern on the lounge chair, as viewed from a right side elevation view thereof.

The broken lines show environmental subject matter and form no part of the claimed design.
